UNITED STATES PATENT OFFICE.

ANDREW B. CLAYTON, OF UNION, NEW JERSEY, ASSIGNOR TO THE SINGER MANUFACTURING COMPANY, OF ELIZABETH, NEW JERSEY, A CORPORATION OF NEW JERSEY.

LOOPER-OPERATING MECHANISM FOR SEWING MACHINES.

Application filed December 7, 1922. Serial No. 605,352.

This invention relates to sewing machines, more particularly of the single-thread chain-stitch type having an oscillating loop-taker or looper, and has for an object to provide 5 a loop-taker operating mechanism of simple construction whereby a slightly increased dwell is given to the loop-taker prior to the beginning of its loop-seizing movement, to give the needle time to throw out a needle-loop large enough for certain seizure by the 10 loop-taker. In machines of the single-thread chain-stitch type it is desirable that the needle-loop be shed from the looper as quickly as possible after such loop has been entered by the descending needle, so that the 15 remaining portion of the down-stroke of the needle will be sufficient to tighten the shed needle-loop, and a further object of the invention is not only to slightly delay 20 the beginning of the advancing movement of the looper, to give the needle added time to throw out a loop, but also to accelerate the latter portion of the retracting motion of the looper to hasten the shedding of the 25 needle-loop after the needle enters it.

Another object of the invention is to interconnect the needle and loop-taker so that they will cooperate in accurately timed relation without danger of such relation 30 being lost by slippage or wear of moving parts.

To the attainment of the ends in view, the loop-taker shaft is connected to be actuated by a guideway and follower connection 35 with the vertical needle operating pitman in the bracket-arm standard. The guideway is preferably displaced at a slight angle from a line normal or at right angles to the longitudinal axis of the pitman, the angle of displacement from the normal line being preferably in the same direction as the direction 40 of rotation of the main-shaft which actuates the pitman. This disposition of the guideway causes the loop-taker to dwell slightly 45 as the needle starts to rise and thus gives the needle an opportunity to throw out a larger loop and insures certainty of seizure of such loop by the loop-taker. This result is accomplished by the present mechanism while 50 maintaining a minimum distance from the point of the loop-taker to the needle at the beginning of the loop-seizing movement of the loop-taker, which condition permits of a minimum descent of the needle below the

work and a maximum time that the needle is 55 out of the work at which time the feed must be accomplished.

In the accompanying drawings, Fig. 1 is a side elevation of a sewing machine embodying the invention. Fig. 2 is a horizontal 60 section through the bracket-arm standard of the machine showing the bed in plan. Fig. 3 is a vertical section through the standard showing the loop-taker or looper-actuating mechanism at the period of the 65 cycle when the looper is at the end of its loop-seizing stroke and the needle is at its highest point. Fig. 4 is a view of the needle and looper in their respective positions corresponding to the positions of the parts in 70 Fig. 3. Fig. 5 is a view similar to Fig. 3 but at the period in the cycle when the needle is at the end of its down stroke and the looper fully retracted. Fig. 6 is a view of the needle and looper in their respective 75 positions corresponding to the positions of the parts in Fig. 5, and Fig. 7 is a cross section through the looper actuating guideway on the needle-bar operating pitman.

For the purposes of the present disclosure 80 the invention is embodied in a single-thread chain-stitch sewing machine having a frame casting formed with a bed 1, standard 2, and overhanging bracket-arm 3 terminating in the head 4 in which is journaled the presser-bar 5 and reciprocating needle-bar 6 carrying the eye-pointed needle 7 which reciprocates as usual through the needle-hole in the throat-plate 8. Journaled in suitable bearings below the level of the throat-plate 8 85 is the main-shaft 9 carrying a spherical eccentric 10 which is embraced by the lower strapped end of a pitman 11 disposed vertically within the standard 2 and connected at its upper end by means of a ball-and-socket joint 12 to the rearward end of the needle-lever 13. The needle-lever 13 is fulcrumed at 14 on the bracket-arm 3 and at 90 its forward end is connected by means of the usual link 15 to the bracket 16 fixed to the 95 needle-bar 6.

In the particular machine chosen for the 100 purposes of the present disclosure, the loop-taker 16 which cooperates with the needle 7 is of the two-motion non-thread-carrying 105 type common to single-thread chain-stitch machines. This loop-taker or looper is mounted on a looper-shaft 17 parallel to the

main-shaft 9 and having collars 17' thereon to fix it against endwise movement. The looper-shaft 17 has fixed to its rear end a crank 18 which is connected by the link 19 to one arm 20 of the bellcrank-lever 20, 21, fulcrumed on a pin 22 fixed in the standard 2.

The arm 21 of the bellcrank-lever has fixed in its free end a pin 23 having a reduced extremity 24, Fig. 7, entering an apertured slide-block 25 cylindrically surfaced at 26, 26, to fit the cylindrically surfaced guideway 27 in the block 28 mounted on the pitman 11 intermediate the ends of the latter. The pin 22 is located at a level between the upper and lower extreme positions of the guideway 27.

The guideway 27 is preferably not disposed truly at right angles to the longitudinal axis *a*—*b*, Fig. 5, of the pitman 11 but is inclined a little, say 5 or 10 degrees away from a line *n*, normal to the axis *a*—*b*, the guideway 27 being preferably shifted or turned away from the normal line *n* in the same direction in which the shaft 9 rotates, i. e., counter-clockwise, as indicated by the arrows in Fig. 5. The effect of this inclination of the guideway 27 is to cause the bellcrank 20, 21 and looper-actuating connection to dwell in the positions shown in Figs. 5 and 6 while the pitman 11 moves from full line to dotted line position, Fig. 5, thus lowering the upper end of the pitman 11, a slight distance, represented in Fig. 5 by the reference character *d*, and consequently giving a small upward motion to the needle, Fig. 6, before the looper 16 begins its advancing stroke. Regarded from another viewpoint, as the lower end of the pitman 11 is swung to the left from full to dotted line position, Fig. 5, the entire pitman is lowered slightly, represented by the distance *d*. The motion of the pitman to the left, however, shifts a higher portion of the guideway 27 into engagement with the follower 23, thus compensating for the drop of the pitman. The slight upward motion of the needle thus obtained, while the looper dwells, gives the needle an opportunity to throw out a loop of a size sufficient for certain seizure by the looper 16, the point of which it will be noted lies close to the needle in Fig. 6.

When the looper reaches the position in Fig. 4, the link 19 alines itself with the arm 20, Fig. 3, and thus acts as a toggle, causing the looper to dwell for a time which is prolonged by the endwise motion of the guideway 27 at this period of the cycle. It will be observed that during the latter portion of the up-stroke of the pitman 11, the upward motion imparted to the follower 23 is accelerated by the inclined guideway 27 which moves away from the fulcrum 22 and upwardly prior to reaching the extreme uppermost position shown in Fig. 5. The

effect of this acceleration of the latter part of the upward motion of the follower 23 is to accelerate the latter portion of the re-tracting stroke of the looper 16, thus hastening the shedding of the needle-loop and giving the descending needle more time to tighten such loop.

It should also be noted that the loop-taker motion is derived directly from the needle-operating linkage and not through a second crank or eccentric on the main-shaft. The careful relative timing or adjusting of two eccentrics on the main-shaft is therefore not required to time the loop-taker to the needle.

The invention is not to be understood as limited to chain-stitch machines as it is obviously applicable to any sewing machine having a to-and-fro moving loop-taker.

Having thus set forth the nature of the invention, what I claim herein is—

1. In a sewing machine, a reciprocating needle, a looper having loop-seizing and loop-shedding movements, a main-shaft, an eccentric on said shaft, a member actuated by said eccentric, actuating connections between said member and said needle and loop-taker, said connections including means for delaying the beginning of the loop-seizing movement of the looper relative to the rising movement of the needle until the needle has risen a short distance from the lower limit of its stroke.

2. In a sewing machine, a needle, a needle-carrier, a loop-taker, a main-shaft, an eccentric on said shaft, a connection including a pitman embracing said eccentric for operating said needle-carrier, and an operative connection between said loop-taker and said pitman intermediate the ends of the latter, said last mentioned connection including a guideway and follower elements one of which is carried by said pitman and the other connected to said loop-taker.

3. In a chain-stitch sewing machine, a needle, a rotary driving shaft, an eccentric on said shaft, a pitman embracing said eccentric and connected to reciprocate said needle, said pitman being formed with a transverse guideway which is turned away from a line normal to the longitudinal axis of said pitman in the direction of rotation of said driving shaft, a looper, an oscillatory looper-carrier, and a follower embraced by said guideway and connected to oscillate said looper-carrier.

4. In a sewing machine, a needle, a rotary driving shaft, an eccentric on said shaft, a pitman embracing said eccentric and connected to reciprocate said needle, said pitman being formed with a transverse guideway, an oscillatory loop-taker, and a follower embraced by said guideway and connected to oscillate said loop-taker, said follower being in the form of a lever fulcrumed at a level between the levels of the upper

and lower extreme positions of the guideway.

5. In a chain-stitch sewing machine, a needle, a rotary driving shaft, an eccentric on said shaft, a pitman embracing said eccentric and connected to reciprocate said needle, said pitman being formed with a transverse guideway which is turned away from a line normal to the longitudinal axis 10 of said pitman in the direction of rotation of said driving shaft, a looper, an oscillatory looper-carrier, a follower embraced by said guideway and connected to oscillate said looper-carrier, said follower being in 15 the form of a lever fulcrumed at a level between the levels of the upper and lower extreme positions of the guideway, and the connections between said follower and looper including a toggle device causing the 20 looper to have a prolonged dwell at the end of its loop-seizing stroke.

6. In a sewing machine, a reciprocating

needle, a to-and-fro moving looper, a looper-actuating eccentric, a pitman connected to said eccentric and having a guideway which is turned away from a line normal to the longitudinal axis of the pitman in the direction of rotation of said eccentric, and a follower embraced by said guideway and connected to actuate said looper. 25 30

7. In a sewing machine, a reciprocating needle, a to-and-fro moving looper, a looper-actuating eccentric, a pitman connected to said eccentric and having a guideway which is turned away from a line normal to the longitudinal axis of the pitman in the direction of rotation of said eccentric, and a pivoted follower lever actuated by said guideway and connected to actuate said looper. 35 40

In testimony whereof, I have signed my name to this specification.

ANDREW B. CLAYTON.
